UNITED STATES PATENT OFFICE

FRED CARL, OF INDIANAPOLIS, INDIANA.

DESIGN FOR A RING, PIN, OR ARTICLE OF SIMILAR NATURE.

Application filed May 26, 1922. Serial No. 2,435. Term of patent 7 years.

To all whom it may concern:

Be it known that I, FRED CARL, a subject of the Kingdom of Great Britain, residing at Indianapolis, in the county of Marion and State of Indiana, have invented a new, original, and ornamental Design for Rings, Pins or Articles of Similar Nature, of which the following is a specification, reference being had to the accompanying drawing, forming a part thereof.

The figure is a top plan view of a ring, showing my new design.

I claim:

The ornamental design for a ring, pin, or article of similar nature, as shown.

FRED CARL.
